UNITED STATES PATENT OFFICE.

ADDISON E. AUGUSTINE, OF HACKENSACK, NEW JERSEY, ASSIGNOR TO CHESTER MACHINE CO., INC., OF NEW YORK, N. Y., A CORPORATION OF NEW YORK.

DELIVERY MECHANISM FOR ENVELOPE-MAKING MACHINES.

1,427,083.

Specification of Letters Patent. Patented Aug. 29, 1922.

Application filed December 5, 1919. Serial No. 342,673.

To all whom it may concern:

Be it known that I, ADDISON E. AUGUSTINE, residing at Hackensack, in the county of Bergen and State of New Jersey, have 5 invented certain new and useful Improvements in Delivery Mechanism for Envelope-Making Machines, of which the following is a specification.

This invention relates to delivery mechanism for envelope-making machines.

An object of the invention is to provide a delivery mechanism which is positive and efficient in its operation and which is at the same time of simple and practical construction.

A further object is to provide a delivery mechanism in which free and unobstructed access is given to all the envelopes in the delivery chute at all times.

20 A further object is to construct the device so that certain elements thereof are connected together and assembled with the delivery table so that they may be handled as an entity when placing them into and 25 out of functioning position within the machine.

A more specific object is to provide a pusher for moving the finished envelopes into an appropriate delivery chute and to 30 provide retaining means for holding the envelopes within the delivery chute which is positively operated by the movements of the pusher.

Other objects and aims of the invention, 35 more or less specific than those referred to above, will be in part obvious and in part pointed out in the course of the following description of the elements, combinations, arrangements of parts and applications of 40 principles, constituting the invention; and the scope of protection contemplated will be indicated in the appended claims.

In the accompanying drawings which are to be taken as a part of this specification, and 45 in which I have shown merely a preferred form of embodiment of the invention:—

Figure 1 is a vertical sectional view through a portion of an envelope-making machine including a delivery mechanism 50 constructed and operated in accordance with this invention.

Figure 2 is a diagrammatic illustration for graphically showing the different positions of moving parts present in Fig. 1.

Figure 3 is a top plan view of the structure seen in Fig. 1.

Figure 4 is an enlarged plan view of a portion of the mechanism seen in Fig. 3, and

Figure 5 is a vertical sectional view taken 60 substantially upon the plane of line V of Fig. 1, and looking in the direction of the arrow.

Referring to the drawings for describing in detail the structure which is illustrated 65 therein, is the reference character L indicates a horizontal delivery table at the opposite sides of which rise vertical wall members 1 and 2 so as to constitute a delivery 70 chute or guide-way along which the finished envelopes are fed from the drying chain, (not illustrated) as will be readily understood by those familiar with this class of machines. The envelope is picked out of the drying chain by a picker device, as 3, and 75 is swung around by the picker device into position in front of and upon a pusher plate 4, as indicated by the arrows in Figs. 1 and 2. The pusher plate then moves forward and carries the envelope into position within 80 the chute formed by the table L and the walls 1 and 2, as clearly seen in Figs. 1 and 2. The pusher plate then moves backwardly and receives another envelope which it at 85 once delivers into the chute, the operation being repeated continuously throughout the running of the machine, and the envelopes being stacked one against the other within the chute, each new envelope acting to push forward the stack along the chute. A holder 90 block 5 is preferably present within the chute.

This block is mounted to slide readily along the table and its purpose is merely to hold the envelopes against falling forward. 95 It moves forward readily as envelopes are added to the stack by the pusher plate.

To retain the newly added envelopes from falling back as the pusher plate recedes, upper and lower stops, G and H respectively, are provided. The upper stops G are duplicated at opposite sides of the chute and each consists of a gravity latch member 6 pivotally hung upon a pivot wire 7 carried by a guide plate 8. The plate 8 is arranged horizontally spaced substantially parallel above the upper surface of the table L. It is supported by a bracket member 9 carried by the

wall member 1, or 2. The bracket member is of inverted L-shape. Its shorter leg 10 extends horizontally above the guide plate and its longer leg 11 depends into adjustable engagement with a carrying member 12 supported upon the outer surface of the wall member 1, or 2. The leg 11 is slotted longitudinally, as at 13, to receive a clamp bolt 14 projecting from the carrying member 12, and the carrying member is preferably formed with side flanges 15 forming a vertical guide-way along which the leg 9 may be adjusted at will to alter the elevation of the guide plate 8 above the table L.

15 The side wall members 1 and 2 of the chute are preferably mounted so that they may be moved toward or away from each other in order to better accommodate envelopes of different lengths. For this purpose the wall members 20 may be carried upon horizontal rods 16 which are adjustably mounted within bearings 17 carried by stationary supporting plates 18. Suitable screws, as 19, or other means, may be employed for retaining the walls 1 in any position of lateral adjustment relative to the plates 18. Since the bracket members 9 are carried solely upon the wall members 1 and 2 it is apparent that they will move toward or away from each other whenever the wall members are moved. In this way the stops G are always maintained in proper position for cooperating with envelopes of the respective sizes for which the walls 1 and 2 are adjusted to cooperate. At 35 the same time a wide open space 20 is afforded between the two stops G where nothing overlies the upper edge of the stacked envelopes. This is important in that it affords free and unobstructed access to all of the envelopes in the stack at any time. It also avoids necessity for independent adjustment of the stops G whenever the side walls 1 and 2 are adjusted.

The lower stop H consists of a plate 21 carried by a bracket 22 which is pivotally mounted, as at 23, between suitable legs 24 fixed to or formed integral with the table L at the under surface thereof. This plate is provided with a plurality of fingers 25 which normally project upwardly through registering openings 26 formed through the table so that the upper ends of these fingers are adapted to constitute directly the lower stops for the envelopes. A tension spring 27 is arranged for urging the bracket 22 upwardly to hold the fingers in stopping position.

The pusher plate 4 is carried by an arm 28 which is pivotally mounted upon a shaft 29 and which has an extending portion 30 connected by a link 31 with a rocker member 32 carrying a roller 33 in the path of a cam 34. The cam 34 is mounted upon a shaft 35, and the movements of the cam, supplemented by the action of a tension spring 36 connected with the extension 30, causes swinging

movement of the pusher plate between its two positions; that is, between its rearward or receiving position, and its forward or delivering position. The extension 30 may, if desired, be provided with a slot 37 longitudinally therein to be engaged by the pivot bolt 38 of the link 31 so that the point of connection of the link with the extension 30 may be adjusted at will for altering the precise extremes to which the pusher plate is moved by the cam.

Projecting from the side of the arm 28 is a pin 39 arranged for engaging a cam plate 40 which is carried by the bracket 22. The cam plate 40 is pivotally mounted upon the bracket 22, as at 41, and is held against swinging in a downward direction by means of a stop portion 42 formed upon the bracket. The relation of the pin 39 and the cam plate is such that as the arm 28 moves forward to delivering position the pin will engage the upper surface of the cam plate and ride therealong causing the cam plate and consequently the bracket 22 carrying the stops H, to swing downwardly until the pin rides off of the upper end, as 43, of the cam plate and allows the spring 27 to return the parts to their normal position.

As seen by a study of Fig. 2, the parts are so arranged that the stops H are held in a position below the upper surface of the table L at a time while the envelope, as 44, is passing over said stops.

As the arm 28 returns to its receiving position, the pin 39 engages the under surface of the cam plate and swings the cam plate upwardly, as seen in Fig. 1. When the pin has passed the cam plate falls again to its position against the stop 42 ready for a subsequent movement of the pin along the upper surface of the cam plate.

The lower edge of the pusher plate is, of course, suitably formed, as at 45, for allowing the pusher plate to return after the stops H have moved upwardly to stopping position behind the delivered envelope.

The table L is detachably connected with the main frame work 46 of the machine by means of suitable screws, or the like, as 47, the removal of which will permit the table to be lifted entirely away from the machine. The heads of the screws 47 are directly in the face of the table so that they may be very easily taken out whenever occasion arises for the making of repairs or adjustments to the mechanism above described. This is of considerable importance in view of the fact that the supporting plates 18, and with them the side wall members and the upper stops, as well as the lower stops and their carrying bracket, are all mounted directly upon the table so that they are all bodily removable as a single entity with the table.

The supporting plates 18 may be con-

nected with the table L in any manner, but for convenience are shown as being fixed to the side portions of the table by screws or the like, as 48.

5 As many changes could be made in this construction without departing from the scope of the invention as defined in the following claims, it is intended that all matter contained in the above description, or 10 shown in the accompanying drawings, shall be interpreted as illustrative only and not in a limiting sense.

The table L may be formed with an abutment portion 49 arranged as a stop to be 15 engaged by the upper portion of the bracket 22 for limiting the upward movement of said bracket.

The side wall members 1 and 2 may have 20 portions cut therefrom to provide openings 50 for facilitating unobstructed movement of said side walls without interfering with the operation of the stops 8.

Having thus described my invention, what I claim as new and desire to secure by Letters Patent is:—

1. A delivery mechanism for envelope-making machines comprising a receiving table, a pusher for delivering the envelopes upon the table, means to operate the pusher, 30 and an envelope retaining stop arranged to be operated directly by said pusher.

2. A delivery mechanism for envelope-making machines comprising a receiving table, a pusher for delivering the envelopes upon the table, means to operate the pusher, 35 an envelope retaining stop, and a mechanical connection between said stop and said pusher for operating said stop directly by the pusher.

40 3. A delivery mechanism for envelope-making machines comprising a receiving table, a pusher for delivering the envelopes upon the table, an envelope retaining stop, and cam controlled means cooperative between said stop and said pusher for moving 45 the stop in response to the movements of the pusher.

4. A delivery mechanism for envelope-making machines comprising a receiving 50 table, a pusher for delivering the envelopes upon the table, an envelope retaining stop, a pivoted carrying bracket for said stop, means urging said bracket to a position with 55 said stop in stopping position, and means carried by said pusher arranged for engaging the bracket to move the stop out of stopping position in response to the movements of the pusher.

5. A delivery mechanism for envelope-making machines comprising a receiving 60 table, a pusher for delivering the envelopes upon the table, an envelope retaining stop, a pivoted carrying bracket for said stop, a spring arranged for urging the bracket into 65 a position with said stop in stopping posi-

tion, said bracket providing a cam surface portion, a member carried by the pusher arranged for engaging said cam surface portion to move the bracket into position with said stop out of stopping position at 70 a time when an envelope is being moved on to said table, and means whereby said cam surface portion and said part carried by the pusher are cooperative to permit the carrier to move into a position with said 75 stop in stopping position at a time when said envelope has been fully delivered on to the table.

6. In a delivery mechanism for envelope-making machines, the combination with a 80 supporting frame, of a table, upper and lower stop members carried by the table, and means whereby said table with said parts carried thereby is bodily removable from said frame. 85

7. In a delivery mechanism for envelope-making machines, the combination with a supporting frame, of a chute comprising a table having opposite side wall members and having upper and lower envelope stops all 90 carried by said table, and means whereby said table, with all of said parts carried thereby, is bodily removable from said frame.

8. In a delivery mechanism for envelope-making machines, the combination with a supporting frame, of a chute comprising a substantially flat table, a pair of standards fixed to said table and rising above the surface thereof, opposite side wall members for the chute carried by and adjustable upon said standards, movable back and forth over the surface of said table to alter the width of the chute of which the table forms the bottom wall, and means whereby 100 said table with all of said parts carried thereby is bodily removable from said frame. 105

9. In a delivery mechanism for envelope-making machine, the combination with a 110 supporting frame, of a chute comprising a substantially flat table, a pair of standards fixed to said table and rising above the surface thereof, opposite side wall members for the chute carried by and adjustable upon 115 said standards movable back and forth over the surface of said table to alter the width of the chute of which the table forms the bottom wall, upper and lower envelope stops carried by said table, and means 120 whereby said table with all of said parts carried thereby is bodily removable from said frame.

10. A delivery mechanism for envelope-making machines comprising a delivery 125 chute made up of a table and a pair of side wall members, means whereby said side wall members are adjustable relative to each other, stop supporting members carried by and adjustable with said side wall members, 130

5 said stop supporting members comprising parts standing in positions overhanging the chute adjacent the respective side wall members, and stops carried by said supporting members depending from the mentioned parts thereof into said chute.

10 11. A delivery mechanism for envelope-making machines comprising a delivery chute made up of a table and a pair of side wall members, a pair of stop supporting members, said supporting members comprising parts standing in positions overhanging the chute adjacent the respective side wall members, means whereby said supporting members are adjustably connected with the side wall members to move the mentioned parts of the stops toward and away from the table, stops carried by said supporting members depending from the mentioned parts 15 thereof into said chute, and means whereby said side wall members are adjustably supported by said table.

20 12. A delivery mechanism for envelope-making machines comprising a receiving table, a pusher for delivering the envelopes upon the table, means to operate the pusher, an envelope retaining stop, and a part carried by and movable with the pusher arranged to engage the stop to operate the stop 25 directly from the pusher.

30 13. In a delivery mechanism for envelope-making machines, the combination with a supporting frame, of a chute comprising a substantially flat table resting upon an upper surface portion of said frame, opposite side wall members for the chute, means whereby said side wall members are adjustable toward and away from each other back and forth over the surface of said table to 35 alter the width of the chute, and retaining means extending downwardly through said table into engagement with said supporting

frame, said retaining means being accessible from above the table and adapted to facilitate removal of the table and parts carried thereby from said supporting frame. 45

14. A delivery mechanism for envelope-making machines comprising a receiving table, a pusher for delivering the envelopes upon the table, an envelope retaining stop, means urging said stop normally to stopping position, two members one connected with said stop and the other connected with said pusher cooperative to move the stop out of stopping position when an envelope is 50 being delivered by the pusher on to the table, and said two members being cooperative also to permit the stop to move to stopping position when the envelope has been 55 fully delivered on to the table. 60

15. A delivery mechanism for envelope-making machines comprising a receiving table, a pusher for delivering the envelopes upon the table, an envelope retaining stop, means urging said stop normally to stopping position, two members one connected with said stop and the other connected with said pusher cooperative to move the stop out of stopping position when an envelope is being 65 delivered by the pusher on to the table, said two members being cooperative also to permit the stop to move to stopping position when the envelope has been 70 fully delivered on to the table, and said two members being cooperative also to permit return movement of the pusher without moving the stop 75 from stopping position. 75

In testimony whereof I affix my signature in the presence of two witnesses.

ADDISON E. AUGUSTINE.
